UNITED STATES PATENT OFFICE.

ANDREW W. GRAHAM, OF BUFFALO, NEW YORK.

COMBINED CIGARETTE AND MATCH CASE.

Application filed August 11, 1923. Serial No. 856,802.

To all whom it may concern:

Be it known that I, ANDREW W. GRAHAM, citizen of the United States, residing at Buffalo, in the county of Erie and State of New York, have invented certain new and useful Improvements in Combined Cigarette and Match Cases, of which the following is a specification.

This invention relates to carrying cases such as are used to carry articles in person's pockets, and has special reference to a combined cigarette and match carrying case.

It is common among smokers to carry packages of cigarettes and matches, such as the ordinary box of safety matches loose in the pockets. It frequently happens that when a smoker desires to smoke a cigarette or the like, he has to hunt in one pocket for the cigarette, and in another pocket for his box of matches.

One important object of the present invention is to provide an improved carrying case so arranged and constructed as to be especially adapted for receiving and holding a package of cigarettes and a box of matches, the whole being arranged in a neat and compact manner so that it may be carried in the side pocket of a coat without causing undue bulging or distortion of the garment.

Furthermore, it frequently happens that either the safety matches commonly used are not procurable, or through personal choice, the ordinary matches which strike on any surface are preferred.

A second important object of the invention is to provide an improved case adapted to hold in one end a package of cigarettes, small cigars, or the like, and in the other end either a box of safety matches or loose matches of the kind which may be struck on any surface.

It is desirable, in a device of this character, to provide means on the case itself, or accessible through an opening in the case for the striking of matches, so that in the event of wet weather there will always be a dry surface on which a match may be struck.

A third important object of the invention is to provide an improved combined cigarette and match carrying case so constructed and arranged that either the striking surface of a safety match box may be exposed for use through a suitable opening, or a sur-

face for striking ordinary matches may be exposed through the same opening, the result being accomplished by the employment of a reversible match box holder within the case.

Devices of this character are peculiarly adapted for use as advertising articles on account of the wide distribution which may be accomplished by the employment of such devices with advertising matter thereon.

A fourth important object of the invention is to provide an improved cigarette and match case, which may be manufactured very economically and out of cheap material so that it may be used for advertising purposes by printing on such surfaces as may be desired.

When not in use it is desirable to have cases of this description collapsible, so that they may be carried flat in a pocket or packed in a small compass. This is particularly valuable where the devices are manufactured of cheap materials and used for advertising.

A fifth important object of the invention is to provide an improved match and cigarette case which is collapsible and adapted to be packed or carried in a flattened out condition.

With the above and other objects in view as will be hereinafter apparent, the invention consists in general of certain novel details of construction and combinations of parts hereinafter more fully described, illustrated in the accompanying drawings and specifically claimed.

In the accompanying drawings, like characters of reference indicate like parts in the several views, and:

Fig. 1 is a perspective view of one preferred form of the invention.

Fig. 2 is a front view thereof with the top flap opened up.

Fig. 3 is a horizontal section therethrough showing one form of the device in its expanded position, the view being on the line 3—3 of Fig. 2.

Fig. 4 is a view similar to Fig. 3 with the box collapsed.

Fig. 5 is a perspective view of a stiffener adapted to be inserted in the cigarette carrying side of the case.

Fig. 6 is a perspective view of a stiffener and match receptacle adapted to be inserted in the match compartment of the case.

Figures 7 and 8 are perspective views of modifications.

Fig. 9 is a section on the line 9—9 of Fig. 8.

It is to be understood that the case, forming the subject of this invention, may be manufactured from a wide variety of materials. It may be made from cardboard, paste board, mill-board, or other paper products, and this may be left plain or covered with an ornamental covering, such as pebbled paper, one of the paper imitations of leather or fabric, or any similar material. The foundation may also be covered with fabric itself, or with thin leather or any like material. Furthermore, the case may be made of more expensive materials, such as leather, or leather imitations, and in the non-collapsible forms, even metal may be used, although it is preferred to have the forms collapsible.

Again, it is obvious that the device may be either with or without ornamentation and that, especially in the cheaper forms, adapted to be given away, advertisements may be printed in the various blank spaces of the sides.

In any event, the invention consists of a casing having a back 10, and front wall 11. The back piece is of greater vertical dimensions than the front wall 11, and thus forms a top flap 12 and front flap 13, which is adapted to fold over the front wall 11 and be connected thereto by means of a snap button fastener having a button part 14 and socket 15, as shown in Fig. 2. It is of course obvious that other fastening means may be employed, the snap button being merely typical of a suitable fastening means. Preferably, the top portion and the front flap 13 are defined from the other parts by creased lines 16 forming fold lines. At the bottom the front and back are connected by means of a bottom piece 17, and at the ends end closures 18 are employed, one of which has an elongated opening 19 therein for the purpose of exposing the striking surface of a match box when in position in the case. Between the ends 18 is arranged a partition 20, and when these cases are made of paper like materials, the ends and bottoms are provided with creased lines, as indicated at 21 in Fig. 3, so as to enable the ends, bottom and partition to be folded up and the front and back to collapse toward each other, this being clearly shown in Fig. 4. In the cheaper forms of the device, the package of cigarettes is dropped into the larger compartment of the two formed by the partition 20, while the match box is dropped into the smaller compartment with its side carrying the striking strip, exposed through the opening 19. In the better forms of the device, it is preferred to employ in each of the compartments a liner box, the cigarette liner

box being shown at 22 in Fig. 5, and consisting of a box opened at the top and made from some suitable stiff material. The material of which this and the other liner is made must be of reasonable stiffness but need not be of any particular character, although it may be found preferable in the more expensive leather cases to provide a metallic liner made, for instance, of thin nickelated brass or the like. The liner for the match compartment or match box compartment consists of an open topped box 23, as shown in Fig. 6, and having at one side edge a slot 24 arranged to register with the slot 19 when the box is inserted in one position. On the side opposite the slot 24, there is provided a roughened striking surface 25 on the box which is exposed through the slot 19 when the box is inserted in a reversed position. Thus the box may be used with the slot 24 registering with the slot 19, and under these conditions, is adapted for the insertion of a safety match box so that the striking strip on such match box will be exposed through the slots 19 and 24. If a person desires to use the case to hold cigarettes and the ordinary non-safety type of matches, he simply removes the liner 23, and reverses its position, so that the imperforate side bearing the roughened striking surface 25 closes the slot 19, thus preventing the escape of matches through such slot when held loosely in the liner, it being obvious that the partition 20 will close the slot 24 in the liner itself at the same time.

In using the ordinary safety matches, one end of the drawer in the box will be cut out or broken out so as to expose the ends of the matches when the top of the case is open.

In the form shown in Fig. 7, it will be observed that the flap 13 and top 12 are split into two parts, as indicated at 12^a and 12^b and 13^a and 13^b. In this form access can be had to either compartment without opening the other.

In the form shown in Fig. 8, separate flaps 13^a and 13^b are provided for the two compartments, the flaps 13^a covering the end of the case instead of the top so that the cigarettes or cigars may be dropped in the end. This form is particularly adapted for carrying cigars since the larger compartment can be made as long as desired, although of course, it may be made of just the proper size to fit a cigarette package.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but

it is wished to include all such as properly come within the scope claimed. For instance, as heretofore mentioned, the sides of the case may be used for advertising, and the construction may be made as cheaply or expensively as desired. Furthermore, it is to be noted that this case is particularly adapted for automobiles since a small holder may be attached in a suitable place in the automobile, and when the user gets into his position, the case may be removed from his pocket and dropped into the holder.

Having thus described the invention, what is claimed as new, is:

1. In a structure of the character described, a main receptacle of a rectangular shape, a partition in said receptacle dividing the same into end compartments, said receptacle having an end wall provided with an elongated opening communicating with one of the end compartments and said compartments each having an inlet, closure means for the inlets movable into and out of a closing position and adapted to be releasably secured in a closed position, and auxiliary receptacles formed of rigid material and each open at one end, said aux-

iliary receptacles being inserted into the end compartments of the main receptacle and filling the same and one having a side wall provided with a match striking surface to be exposed through the opening in the end wall of the main receptacle and a second side wall provided with an elongated opening for registering with the opening in the end wall of the main receptacle according to the position in which the auxiliary receptacle is positioned in the main receptacle.

2. A device of the character described comprising a main receptacle, a partition dividing the main receptacle into end compartments, said compartments being of an uneven size and each having an open inlet end, closure means for the open ends of said compartments movable into and out of a closing position, and auxiliary receptacles of rigid material fitting into the end compartments of the main receptacle and filling the same.

In testimony whereof I affix my signature.

ANDREW W. GRAHAM.
